(57) **CLAIM**

The ornamental design for a shoe, as shown and described.

DESCRIPTION

The present application is related to a co-pending design application Ser. No. 29/699,176, filed concurrently with the present application, the application being in the name of inventor Chris Vella and entitled "Shoe," and all of which is incorporated by reference herein in its entirety.

FIG. 1 is a top, left, and front perspective view of an ornamental design for a shoe;

FIG. 2 is a front elevational view of the shoe of FIG. 1;

FIG. 3 is a rear elevational view of the shoe of FIG. 1;

FIG. 4 is a left side elevational view of the shoe of FIG. 1;

FIG. 5 is a right side elevational view of the shoe of FIG. 1;

FIG. 6 is a top plan view of the shoe of FIG. 1; and,

FIG. 7 is a bottom plan view of the shoe of FIG. 1.

The dash-dash-dash broken lines are included for the purpose of illustrating portions of the shoe that form no part of the claimed design. The dash-dot-dash lines are included for the purpose of illustrating boundary lines and form no part of the claimed design.
